United States Patent Office

Des. 220,062
Patented Mar. 2, 1971

220,062

BONDER

William H. Hill and Robert C. Botting, Carlsbad, Calif.,
assignors to Hughes Aircraft Company, Culver City,
Calif.

Filed Oct. 3, 1969, Ser. No. 19,408

Term of patent 14 years

Int. Cl. D15—05

U.S. Cl. D55—1

Fig. 1

Fig. 2.

Fig. 3.

FIG. 1 is a front elevational view of a bonder showing the new design;

FIG. 2 is a top plan view thereof;

FIG. 3 is a left end elevational view thereof;

FIG. 4 is a right end elevational view thereof;

FIG. 5 is a rear elevational view thereof;

FIG. 6 is a bottom view thereof, on a reduced scale.

We claim:

The ornamental design for a bonder, substantially as shown.
